UNITED STATES PATENT OFFICE.

PERRY O. WHEELER, OF YOUNGSTOWN, OHIO.

STEP.

1,103,719.

Specification of Letters Patent. Patented July 14, 1914.

Application filed February 12, 1914. Serial No. 818,401.

To all whom it may concern:

Be it known that I, PERRY O. WHEELER, a citizen of the United States, residing at Youngstown, in the county of Mahoning 5 and State of Ohio, have invented certain new and useful Improvements in Steps, of which the following is a specification.

This invention relates to an improved step which is formed of sheet metal, and 10 which is intended to be used upon poles, such as telephone poles so that a lineman can climb the pole.

The principal object of the invention is to provide a step which is so constructed that 15 it will fit closely to the pole with its edges sunk in the pole, and to so construct the step that ice can not form upon the upper face of the step.

Another object of the invention is to so 20 construct the step that the outer edge portion will form an abutment lip to prevent the lineman's foot from slipping off the step.

Another object of the invention is to pro- 25 vide a step which can be very cheaply made from a blank of sheet metal, and which can be very easily and quickly put in place.

This invention is illustrated in the accompanying drawings wherein—

30 Figure 1 is a side elevation showing the step applied to a pole; Fig. 2 is a view similar to Fig. 1 with one portion of the pole broken away and the step shown in vertical section; Fig. 3 is a view showing the pole 35 in cross section and the step in top plan; Fig. 4 is a perspective view of the step; Fig. 5 is a view of the blank from which the step is formed.

The step is formed from the blank shown 40 in Fig. 5, which blank is bent along the dotted lines 10 to form the outer wall 11 and side walls 12 of the step. This blank is provided with an enlargement which extends from the upper edge and forms the 45 abutment lip 13.

When the blank is bent to assume the shape shown in Fig. 4, the inclined edges 14 of the blank will fit against the side of the pole 15 while the outer wall 11 will extend 50 from the pole at an incline. Openings 16 are formed in the wall 11 to admit the securing screws 17. These screws 17 when tightened will draw the step into close contact with the pole and will cause the edges 55 14 of the side walls 12 to dig into the pole.

The step will now be very securely held to the pole and will be prevented from having any movement whatever which would tend to wrench the step loose. By having the side walls dig into the pole, the step is 60 prevented from having any transverse movement which would tend to bend or loosen the screws 17. By having the step formed of sheet metal, the step will be hollow and therefore water will run through the step instead of collecting upon the upper face 65 of the step and forming ice as would be the case if a solid step were used. The abutment lip 13 prevents any danger of the lineman's foot slipping off the upper edge of 70 the step when climbing the pole. There has thus been provided a step which can be very cheaply manufactured from sheet metal and which may be very securely connected with 75 a pole. It should also be noted that the step will not quickly wear out and that the step may be easily removed from the pole without damage to the step and can again be used when desired.

What is claimed is:

1. A step formed from a sheet metal blank provided with fastener-receiving openings and provided with an extension leading from its upper edge, said blank being bent longitudinally to form the outer wall and side walls of the step, the extension forming an abutment lip at the upper end of the outer wall of the step, the side edges of said blank being cut at an incline whereby when said blank is bent to form the complete 85 step, the edges of the side walls will fit tightly against a pole and the outer wall will extend from the pole at an incline thereto.

2. A step formed from a sheet metal blank 90 bent longitudinally to form the outer wall and side walls, said outer wall being of greater height than said side walls to form an abutment lip, and means for connecting said step with a pole whereby the side walls 95 may be caused to dig into a pole to assist in holding the step firmly upon the pole.

3. A step provided with an outer wall and side walls leading from said outer wall to form a hollow step and prevent water 105 from gathering upon the upper end of the step and said step being provided with fastener receiving openings.

4. A step of the character described comprising an outer wall, side walls extending 110

from said outer wall, said outer wall extending at an incline to the engaging edges of said side walls, said outer wall having its upper end extending above the edges of 5 said side walls to form an abutment lip and said outer wall being provided with openings for receiving the fastening means.

In testimony whereof I affix my signature in presence of two witnesses.

PERRY O. WHEELER.
